UNITED STATES PATENT OFFICE

HERMANN SCHULER, OF DUSSELDORF, GERMANY, ASSIGNOR TO RHEINISCHE METALL-WAAREN- UND MASCHINENFABRIK, OF DUSSELDORF-DERENDRDORF, GERMANY, A CORPORATION OF GERMANY

ELECTRICAL TIME SWITCH

Application filed November 19, 1929, Serial No. 408,374, and in Germany November 29, 1928.

The present invention relates to a time switch. The object of the invention is to provide a time switch which, by the use of a special means, may be adjusted accurately and by a regulating device having many steps, resulting in minimum deviations from the time of switching for which the switch is adjusted, which deviations do not exceed the permissible limits.

10 In time switch according to the invention gas is produced by a controlled gasifying of liquid effected by electrolysis and gas pressure is used as a driving means for bringing a switch member into a position effecting the release of the desired secondary action, for instance the closure or interruption of the external circuit. The electrolysis is, according to the invention, effected in a closed space of constant volume until the increased gas pressure at a certain height causes removal or destruction of the thin-walled cover plate of a channel or conduit leading to the movable switch member. The released gas pressure then causes a sudden movement of the switch member into the operative position in which it, by making contact, instantaneously effects the release of the desired secondary action. The production of an always equal amount of the gas required for any desired time of 20 switching is effected by the use of the electrolysis in an absolutely exact correspondence with the control of the working current supplied to the time switch.

In the accompanying drawings one construction according to the invention is shown in Figure 1. The illustrated device is particularly adapted for application in connection with a time switch mechanism for an explosive charge which may be used for blasting purposes in mines and for artillery mines as well as projectiles.

Figure 2 is a diagram showing the electrical connections of the device illustrated in Figure 1.

45 The time switch together with the appertaining source of electric current is, for instance, arranged in a wooden casing *a* lined with a metal lining *b*. The gas generator producer consists of a thick-walled hollow vessel *c* of glass or of other acid-proof mate-

rial. The vessel *c* is isolated from and fixed to the bottom of the lining *b* and surrounded by a metal shell *c*₁ so as to be protected against destruction by excessive internal pressure.

55 The upper opening of the vessel *c* is covered by a thin foil *c*₂ of metal or other suitable material. The foil *c*₂ is fixed in position by means of a cover *c*₄ screwed upon the metallic protective sleeve or shell *c*₁. A small central bore *c*₃ is provided in the cover *c*₄ and in an upper cylindrical enlargement of this bore a contact pin *c*₆ is arranged which is axially movable against the pressure of a spring *c*₅ and is insulated from the metal cover *c*₄. The upper end of the contact pin *c*₆ extends into a central bore *d*₁ of the insulating body *d* holding the time releasing device in the casting. At each side of the bore *d*₁, the insulating body *d* carries a contact spring *e*. These contact springs *e* are adapted to cooperate with notches provided in the upper end of the contact pin *c*₆ as soon as this pin is displaced upwardly in the bore *d*₁, thereby holding said pin in the raised position.

75 The glass vessel *c* is filled with an electrolyte, for instance, with a weak acidulous liquid. Two electrodes *f* are fused through the bottom of the glass vessel *c*.

The source *g* of the electric current consists of a galvanic element of well known construction having the electrodes *G*₂ and *G*₃ and a separate glass vessel *g*₁ which contains the acid. The production of current is started only after the destruction of the glass vessel *g*₁ and the flooding of the element *g* with the acid leaving the destroyed vessel *g*₁. A projecting pin *h* is arranged rotatably and longitudinally movable in the housing *a*. This pin *h*, when driven inward manually, 80 will break the glass container *g*₁. The annular resistance *i* seated in a stationary insert *b*₁ in the casing, in connection with the contact spring *l*₁, which slides thereon, constitutes an adjustable resistance in the circuit 85 which extends from the source of current *g* to the electrodes *f* in the gas generator chamber *c* and serves to regulate the strength of the current supplied to the gas generator, 90 and thus to determine the time of ignition. 95 100

By turning the pin *h* about its axis, whereby it carries along the contact spring *i*, by means of the bushing *i*₂, the controlling resistance *i* is adjusted to produce the current strength desired at any time, whereby the adjusted value of the resistance may be indicated and read off from an indicating device including a scale on the stationary cover of the casing and a cooperating mark on the head of the rotatable pin *h*.

The production of current in the element *g* is started by the destruction of the vessel *g*₁ containing the acid. By way of the resistance *i*, previously adjusted to the desired time of ignition, the current is supplied to the electrodes *f* of the gas generator in a quite definite strength. The liquid contained in the vessel *c* is now partly converted into gases by the chemical action of the current passing through the said liquid by way of the electrodes *f*. According to the adjusted strength of current the evolution of gases per unit time is more or less lively. As the vessel *c* is closed, the pressure of the gas increases with the continued evolution of gases until at a quite definite gas pressure the foil *c*₂, closing the bore *c*₃ of the vessel *c*, is disrupted and perforated at this point. The gas now flows against the piston face of the contact pin *c*₄ and suddenly drives this pin between the contact springs *e*. Hereby the element *g*, in a well known manner, is inserted in a circuit closed by a second line *k*, *g*₂, *g*₃, *e*, *k* across an ignition means arranged at a certain distance from the time switch mechanism and this ignition means is thereby ignited and causes detonation of the explosive charge.

What I claim is:

1. In combination in an electric time switch, a source of current; means for controlling the strength of the current delivered from said source of current; a cell for producing gas electrolytically; conducting means completing a circuit which includes the source, the cell and the control means in series; and a circuit closing means constituting a movable closure of the cell, and being movable by virtue of the gas pressure produced in said cell, when said pressure exceeds a definite value, said circuit closing means being adapted to control any desired circuit.

2. In combination in an electric time switch, a source of current; means for controlling the strength of the current delivered from said source of current; a cell for producing gas electrolytically; conducting means completing a circuit which includes the source, the cell and the control means in series; a diaphragm closing the cell, whereby said diaphragm will be disrupted when the gas pressure in the cell exceeds a certain value; and a circuit closing member arranged to be actuated by the gases thus released, said circuit closing member being adapted to control any desired circuit.

3. A device as described in claim 1, where-in the source of current is a galvanic cell which is normally free from electrolyte, and is put into service by adding the electrolyte when it is desired to operate the device.

4. A device as described in claim 1, where-in the source of current is a galvanic cell which is normally free from electrolyte, and wherein the said electrolyte is stored in a sealed vessel, adjacent the cell; and means manually actuatable from outside the device provided to open said sealed vessel and allow it to discharge its contents into the galvanic cell to cause the same to produce electricity, when it is desired to operate the device.

In testimony whereof I have affixed my signature.

HERMANN SCHULER.
